Harry Jacobson
ATTORNEY

UNITED STATES PATENT OFFICE.

LOUIS KRIZS, OF NEW YORK, N. Y.

PUSH-LOCK.

1,369,820.

Specification of Letters Patent.

Patented Mar. 1, 1921.

Application filed June 18, 1920. Serial No. 389,807.

To all whom it may concern:

Be it known that I, LOUIS KRIZS, citizen of Hungary, residing at New York, in the county of New York and State of New York, have invented certain new and useful Improvements in Push-Locks, of which the following is a specification.

This invention relates to latches and especially to that type which is mechanically released by the pressing of a button.

The object of this invention is the provision of a small, simple and inexpensive latch adapted for use in furniture, windows, cabinets and the like, in which it is desirable, on occasion, to hold relatively movable parts stationary.

A further object of this invention is the provision of a latch consisting of few parts which may be quickly and easily assembled and which cannot readily get out of order.

To attain the above and other objects, I employ the devices shown in their preferred forms in the accompanying drawing, in which—

Figure 1 is a horizontal section of my device on line 1—1 of Fig. 2.

Fig. 2 is a rear view of my device.

Fig. 3 is a perspective view of the latch bolt and of the spring actuating the same.

Fig. 4 is a horizontal section of part of a window to which my device has been attached for locking a sash in position.

In the practical embodiment of my invention, the U-shaped frame 10 is held to frame 35 plate 11 by suitable tenons 12 passed through mortises in said plate, the outer ends of said tenons being slightly spread to hold the parts firmly together. A push button 13 passing through a suitable opening in plate 40 11, is provided with a spring post 14 and a collar 15, both integral with said button, said collar being arranged to engage the under side of said plate, the extremity of said post passing through an opening 16 in frame 10. For normally holding button 13 45 in its outermost position, spring 17 is positioned around post 14, one end of said spring abutting against button 13 and the other end against frame 10.

The latch bolt member 18 has a latch bolt 19 at one end thereof, while a follower 20 is positioned at the other end thereof, said follower having an angularly disposed surface 21 on the inner side thereof arranged 55 for engagement with collar 15. Braces 22 join parts 20 and 21, whereby the entire

member 18 can be made in one piece for strength and economy. For use as a window lock, the latch bolt 19 is made cylindrical as shown in Fig. 4. To attach flat spring 60 23 to member 18, suitable notches, equal in width to the thickness of said spring are made in the end of said member near follower 20. After the spring has been inserted into said notches, the metal at the extremities of said notches is spread so as to partly close the notches over the edge of said spring, whereby the spring is firmly held in place.

Pressure on button 13 in the direction of 70 the arrow (Fig. 1) moves collar 15 in the same direction, said collar engaging the edge 21 of follower 20 and moving member 18 against the action of spring 23 to disengage latch bolt 19 from plate 24, which is suitably attached to the cabinet, window frame or piece of furniture, as by screws 25. Release of button 13 causes spring 17 to push said button outwardly, disengaging collar 15 from follower 20 and allowing spring 23 80 to urge the latch bolt into its operative position.

It will be seen that the number of separate parts is reduced to a minimum, and that said parts are readily assembled, so that my 85 device while efficient, is comparatively inexpensive.

What I claim is:—

1. A latch comprising a casing, a bolt-frame 90 slidable in said casing, a bolt formed on one end of said bolt-frame, a beveled offset on the opposite end of said bolt frame, a push-button extending through one wall of the casing and having a shank extending transversely through the said frame, a 95 spring surrounding said shank and normally pressing said push-button outward, and a radially extending peripheral flange formed on said push-button and adapted to engage the said beveled offset on the bolt 100 frame to move the bolt to locking position when the push-button is moved inwardly and to bear against the casing wall to limit the outward movement of said push-button under the influence of the said spring. 105

2. A latch comprising a casing, a bolt-frame 110 slidable in said casing, a bolt formed on one end of said bolt-frame, a beveled offset on the opposite end of said bolt frame, a push-button extending through one wall of the casing and having a shank extending transversely through the said frame, a

spring surrounding said shank and normally pressing said push-button outward, and a radially extending peripheral flange formed on said push-button and adapted to engage 5 the said beveled offset on the bolt frame to move the bolt to locking position when the push-button is moved inwardly and to bear against the casing wall to limit the outward movement of said push-button under the in-

fluence of the said spring, and a bow spring 10 secured to said offset from the bolt-frame and bearing at opposite ends on the wall of the casing and normally urging the said bolt-frame to locking position.

In testimony whereof I have affixed my 15 signature this 17th day of June 1920.

LOUIS KRIZS.
